UNITED STATES PATENT OFFICE.

JAMES A. WOTTON, OF MONTCLAIR, NEW JERSEY, ASSIGNOR TO WESTERN ELECTRIC COMPANY, OF NEW YORK, N. Y., A CORPORATION OF ILLINOIS.

IMPULSE-TRANSMITTER.

1,117,296.

Specification of Letters Patent. Patented Nov. 17, 1914.

Application filed June 14, 1912. Serial No. 703,685.

To all whom it may concern:

Be it known that I, JAMES A. WOTTON, citizen of the United States, residing at Montclair, in the county of Essex and State 5 of New Jersey, have invented a certain new and useful Improvement in Impulse-Transmitters, of which the following is a full, clear, concise, and exact description.

This invention relates to current impulse 10 transmitters, and more particularly to a transmitter adapted to be actuated to send out any one of a plurality of combinations of current impulses over a line to which are connected electroresponsive selective instruments.

The object of this invention is to provide 15 an impulse transmitter which will be compact, sure and quick in its operation and easily and speedily adjusted to send out any particular code of impulses.

The impulse transmitter to which this invention relates comprises generally a clock-work mechanism provided with circuit controlling means adapted in a single operation 20 of the device to complete a selection. The circuit controlling means comprise generally interrupting devices carried by a rotating shaft and operating in connection with spring contacts.

Features of the invention are the means 25 provided for obtaining any desired combination of current impulses by the use of a plurality of adjustable members carried by a single shaft, the means employed for adjusting these members by means of a single knob or handle to send over the line the desired number or combination of current impulses and other details of construction and combination of parts as will hereinafter 30 more fully appear.

In the drawings illustrating this invention—Figure 1 is a horizontal sectional view taken upon line 1—1 of Fig. 3; Fig. 2 is a front elevation illustrating the relation of 45 the dial plates and pointers; Fig. 3 is a rear end view illustrating the gears and cover plates; and Fig. 4 is a detail sectional view taken upon line 4—4 of Fig. 3.

In said drawings, 5 designates a plate 50 upon which is mounted a frame comprising frame-plate members 6 and 7 secured together by rods 8, 8. Supported in the plates 6 and 7 are shafts 9 and 10, the shaft 9 constituting a driving shaft, and the shaft 55 10 the driven shaft of the mechanism.

Loosely mounted upon the shaft 9 is a gear wheel 12 adapted to be driven by a spiral spring 13 mounted upon said shaft. Said gear wheel 12 meshes with a pinion 16 on the shaft 10, which pinion is secured to a gear wheel 17 on said shaft 10, said gear wheel 17 being in mesh with a pinion 18 loosely mounted upon the shaft 9 and secured to a gear wheel 19. The gear wheel 19 meshes with a gear 20 secured to the shaft 10. The gear 20 meshes with a worm on a governor shaft 22 arranged at right angles to the shafts 9 and 10 and supported between projections 23, 23 formed integrally with the frame plate 7. The governor consists of two weighted spring arms 24 and 25 which, as the governor is rotated, are caused to throw their weights outwardly against the inner face of a metal drum 26. The friction of the weights and drum tending to retard the movement of the rotating parts and keep them at a constant speed.

In the design of transmitter shown the impulse mechanism is arranged to put first a preliminary long impulse upon the line, 80 next a succession of short impulses, then to open the line circuit for a short period succeeded by an impulse of substantially the same length as the first preliminary impulse, next a requisite number of short impulses and then maintain battery on the line for a certain period thereafter. The specific mechanism for accomplishing this is as follows: Mounted upon the shaft 10 beyond the frame plate 7 and adapted to rotate 85 with said shaft is a wheel or disk 30 having formed on a portion of its periphery a plurality of teeth 31, 31 which are adapted to coöperate with spring contacts 32 and 33 to alternately make and break a circuit.

Rotatably mounted upon the shaft 10 back of said wheel or disk 30 is an adjustable member 35 normally attached to rotate with said wheel or disk 30 by means of a bowed spring 36 secured to said member 35 100 and being formed to engage depressions 37, 37 in the face of the wheel or disk 30. This adjustable member 35 is for the purpose of regulating the number of teeth on the wheel or disk 30 which will make and break contact between springs 32 and 33 and for this purpose is provided with a portion having the same radius of curvature as the said wheel or disk 30 which extends flush with the outer end of the teeth 31, 31 of said 105 110

wheel or disk. Adjacent to this portion said adjustable member is provided in its periphery with teeth 38, 38 adapted to engage the contact springs 32 and 33 in the same manner as the teeth 31, 31 of said wheel or disk 30. The disk 30 and adjustable member 35 are provided with teeth 34 and 39 respectively of greater width than the teeth 31, 31 and 38, 38 for a purpose hereinafter to be explained. Rotatably mounted upon the shaft 10 to the rear of the adjustable member 35 is a second adjustable member 40 adapted to be moved to cover the teeth 38, 38 of the adjustable member 35. 41 and 42 designate projections formed integrally with the member 35 which serve as stops to limit the movement of the adjustable member 40.

The means provided for the adjustment 20 of the two adjustable members 35 and 40 with respect to each other and with respect to the wheel or disk 30 is as follows:

Rotatably mounted upon the shaft 10 is a gear wheel 50 which is secured to the adjustable member 35 by means of a pin 51 or other suitable means located out of the path of travel of the adjustable member 40. This gear wheel 50 is in mesh with a gear wheel 52 carried by a rotatable sleeve 53 extending 30 through the front plate 5 for the purpose hereinafter set forth. Rotatably mounted upon the shaft 10 to the rear of the gear wheel 50 is a gear wheel 55. This gear wheel is operatively connected with the adjustable member 40 by means of a pin 56 which is secured in the gear 55 and extending through a slot 57 in the gear 50 and through an opening 58 in said adjustable member 40 into a slot 59 in the adjustable member 35, as 40 clearly shown in Fig. 4. The gear wheel 55 is in mesh with a gear wheel 60 secured to a shaft or spindle 61 rotatably mounted in the sleeve 53. As shown the said shaft 61 is reciprocally mounted in the sleeve 53 and normally held in an outward position by means of a coil spring 62 engaging a sleeve 63 secured in a knob 64 and the outer end of the sleeve 53. In this position of these parts a screw pin 65 in the gear wheel 60 is in engagement with one of a plurality of holes 66, 66 in the adjacent face of the gear wheel 52 on the sleeve 53 thus locking the gear wheels 52 and 60 together so that the turning of the knob 64 in this position of the parts will rotate both said gear wheels.

Secured to the sleeve 53 is a pointer 70 adapted as said sleeve is turned to register with characters on a dial plate 71 secured to the plate 5. Stamped upon the pointer 70 are a series of characters with which a pointer 72 carried by the knob 64 are adapted to register. The characters on the dial plate 71 designate the number of teeth on the wheel or disk 30 which will be effective 65 for calling purposes in one revolution of

the shaft 10 while the characters on the pointer 70 designate the number of selective impulses caused by the adjustable member 35 in one revolution of the shaft 10. 75 designates a handle by means of which the 70 mechanism is started.

In the drawings illustrating this invention the pointers 70 and 72 are shown adjusted to the characters 6 and 1 on their respective dials and the interrupting devices 75 are shown in the position which they are designed to assume with the pointers in the position indicated. With the parts in this position the circuit interruptions will be as follows in the operation of the transmitter: 80 First, a long impulse caused by the passage of the tooth 34 under the spring 32; next a series of quick makes and breaks caused by the passage of the teeth 31, 31 under the spring 32, this to be succeeded by a closure 85 of long duration while the periphery of the adjustable member 35, which covers the remaining teeth 31, 31 of the wheel or disk 30, is passing under the spring 32; next a momentary opening of the circuit when the 90 spring 32 drops into a notch just prior to its engagement with the tooth 39; succeeded by a closure equal to the time required for the said tooth to pass under the spring 32, a momentary break occurring just before 95 the first of the teeth 38, 38 engages the spring 32 followed by a long closure caused by the engagement with the spring 32 with the periphery of the adjustable member 40.

Assuming now that it is desired to adjust the parts, say, so that the number of successive quick impulses produced by the wheel or disk 30 will be nine and that produced by the adjustable member 35 will be three. The operation will first turn the knob 64 until 100 the pointer 70 is opposite the index character "nine" on the dial plate 71. This will turn both the gear wheels 52 and 60 and with them the gear wheels 50 and 55. The rotation of the gear wheels 50 and 55 will rotate both the adjustable members 35 and 40 without changing their relation until the adjustable member has uncovered eight 105 of the teeth 31, 31 of the gear or disk 30 or three more than are now shown as uncovered. The next operation will be to press the knob 64 inwardly which will move the gear 60 away from the gear 52 thus disengaging these two gears by moving the pin 65 out of engagement with a hole 66 in the gear wheel 52. If the knob is now rotated until the pointer 72 is opposite the character "three" 110 on the pointer 71 only the gear wheels 60 and 55 will be rotated, thus moving the adjustable member 40 to uncover two more 115 teeth than are now shown as uncovered or three notches between teeth. The knob 64 is then released and the shaft 61 is moved outwardly until the pin 65 in the gear 60 engages the third hole in the gear 52. The 120 125 130

mechanism is then started by means of the handle 75 and rotates the mechanism through one complete revolution. It will be noted that whatever the number of teeth uncovered 5 on either of the toothed members the length of time that the contacts are held closed after the passing thereunder of the teeth 31, 31 and before it reaches the teeth of the adjustable member 35, is also as constant as 10 is also the length of time that the contacts 32 and 33 are maintained closed after the passing thereunder of the exposed teeth of the said adjustable member 35. The gear wheel 60 is made of sufficient thickness so 15 that the amount of movement thereof necessary to disengage the pin 65 from the gear wheel 52 will not move the teeth of said gear wheel 60 out of mesh with the teeth of the gear wheel 55.

20 What I claim is:

1. In an impulse transmitter the combination with a motor-driven shaft, of a toothed wheel carried by said shaft, contact springs adapted to be engaged by the teeth 25 of said wheel for making and breaking a circuit, an adjustable member for determining the number of teeth on said wheel effective for signaling purposes, said adjustable member being provided with teeth adapted to 30 engage said spring contacts independently of the teeth on said wheel, a second adjustable member for determining the number of teeth on said first mentioned adjustable member effective for signaling purposes, and ad-

justing means including a tensioned shaft 35 adapted in one position to move said first mentioned adjustable member relative to said wheel and in another position to move said second mentioned adjustable member with respect to said first mentioned adjustable member.

2. In an impulse transmitter the combination with a rotatable shaft, of a toothed wheel carried thereby, contact springs adapted to be engaged by the teeth of said wheel 45 for making and breaking a circuit, an adjustable member for determining the number of teeth on said wheel effective for signaling purposes, said adjustable member being provided with teeth adapted to engage 50 said spring contacts independently of the teeth on said wheel, a second adjustable member for determining the number of teeth on said first mentioned adjustable member effective for signaling purposes, a rotatable 55 sleeve, a shaft mounted in said sleeve, means for operating both said adjustable members from said sleeve, and means for operating the second named adjustable member from said shaft independently of the movement 60 of the first named adjustable member.

In witness whereof, I hereunto subscribe my name this 13th day of June A. D., 1912.

JAMES A. WOTTON.
